UNITED STATES PATENT OFFICE

171,629

MOBILE FOOD DISPENSER

John W. Williams and Betty Jean Wheeler,
Fort Worth, Tex.

Application January 15, 1953, Serial No. 23,156

Term of patent 14 years

(Cl. D81—10)

To all whom it may concern:

Be it known that we, John W. Williams and Betty Jean Wheeler, both citizens of the United States and both residing at Fort Worth, in the county of Tarrant and State of Texas, have invented a new, original, and ornamental Design for a Mobile Food Dispenser, of which the following is a specification, reference being had to the accompanying drawings, forming a part thereof.

Figure 1 is a perspective view of a mobile food dispenser showing our new design.

Figure 2 is a perspective view of the opposite side of the mobile food dispenser shown in Figure 1.

We claim:

The ornamental design for a mobile food dispenser, substantially as shown.

JOHN W. WILLIAMS.
BETTY JEAN WHEELER.
